[57] CLAIM

The ornamental design for a flair bottle, as shown and described.

DESCRIPTION

FIG. 1 is a perspective view showing the flair bottle of my new design, including the configuration of the cap section; FIG. 2 is a front elevational view thereof;

FIG. 3 is a top view thereof;

FIG. 4 is bottom view thereof;

FIG. 5 is a side elevational view thereof;

FIG. 6 is a rear elevational view thereof;

FIG. 7 is a perspective view, similar to FIG. 1, but illustrating a second embodiment of the invention;

FIG. 8 is a front elevational view thereof;

FIG. 9 is a bottom view thereof;

FIG. 10 is a top view thereof;

FIG. 11 is a side elevational view thereof; and,

FIG. 12 is a rear elevational view thereof.
